Primary Examiner — Antoine Duval Davis(74) *Attorney, Agent, or Firm* — Seyfarth Shaw LLP;
Brian Michaelis(57) **CLAIM**

We claim the ornamental design for a rangefinder, as shown and described.

DESCRIPTION

FIG. 1 is a right side view of the rangefinder.

FIG. 2 is a left side view of the rangefinder of FIG. 1.

FIG. 3 is a top view of the rangefinder of FIG. 1.

FIG. 4 is a bottom view of the rangefinder of FIG. 1.

FIG. 5 is a front view of the rangefinder of FIG. 1; and,
FIG. 6 is a rear view of the rangefinder of FIG. 1.Broken lines shown in the drawings form no part of the
claimed design.**1 Claim, 6 Drawing Sheets**| (56)	References Cited
